UNITED STATES PATENT OFFICE

2,334,315

DENTAL AMALGAMATOR

Edward L. Chott, Chicago, Ill.

Application June 3, 1942, Serial No. 445,561

6 Claims. (Cl. 259—72)

This invention relates to amalgamators, and more particularly to dental amalgamators, as employed in dental laboratories for amalgamating or triturating materials or alloys, such as mercury and another metallic substance for making dental fillings.

One of the desideratum of an amalgamator is that it produces a very thorough amalgamation or mixing of the materials or substances, such as mercury and metallic alloys in a minimum of time, and with a minimum of labor, especially as compared with the ordinary mortar and pestle, or other hand operated devices, or even vibrators or oscillators. An object of the present invention is therefore to provide an improved and novel amalgamator, which is not merely a vibrator or oscillator, but which provides means whereby the mortar or capsule holding the ingredients to be amalgamated in conjunction with a pestle or pellet therein for thorough disintegrating and amalgamating the ingredients, so as to assist and speed up the amalgamation, will be moved in several directions, so as to have the direction of its axes of motion changed and moved at each revolution and in every essential way to produce a quicker and more thorough amalgamation.

Another object of the invention is to provide an improvement upon the device shown in my prior patent, No. 2,201,428, dated May 21, 1940, in that the device is not only more compact and facilitates packing and shipping due to the absence of projecting parts but greatly facilitates the insertion and removal of the capsule mortar and produces an improved motion, which accomplishes a better mixing or amalgamation in less time.

By means of the present invention, the mortar and pestle, together with the ingredients to be mixed, will be moved in a somewhat circular motion in a substantially diamond shaped or oval path in a vertical direction, but will also be moved with a side to side motion in a horizontal direction, with the mortar changing the direction of its axes at each revolution of the driving shaft, so that the ingredients to be amalgamated will be agitated or vibrated and shaken in every essential way to produce a better and more efficient mixture or filling in less time than heretofore required. Also, whereas with my prior device an oscillating or arcuate reciprocating motion is imparted to the mortar longitudinally thereof on a horizontal axis or on its longitudinal axis and a simultaneous oscillation on a substantially vertical axis, or an axis substantially at

right angles to the axis of the first motion, that is, on its central transverse axis, which passes substantially radially through said shaft and simultaneously oscillating or reciprocating the same in a vertical arc on its longitudinal axis, the present device oscillates on its transverse axis, which passes axially through the drive shaft and on a horizontal axis, instead of a vertical axis, and simultaneously oscillates the mortar on its longitudinal axis or reciprocates the same in an arcuate path on said axis extending vertically instead of horizontally, and in which the supporting means for the capsule mortar extends out horizontally from and beyond the end of the drive shaft for more convenient accessibility and compactness, instead of extending upwardly or in a vertical direction.

Another object of the invention is to provide means for operating the amalgamator for any set period of time between one second and a minute or sixty seconds, and causing it to automatically cease operating, or stop at the end of such period, so that the amalgamating action will take place for any period desired according to and best suited for a particular mixture with different percentages of different ingredients, such as mercury and an alloy, whereby a more efficient filling will be produced. By means of the present invention, amalgamation may be produced with improved results in less time than heretofore required.

Further objects and advantages will appear and be brought out more fully in the following specification, reference being had to accompanying drawing, in which:

Fig. 1 is a side elevation of a dental amalgamator in accordance with the invention.

Fig. 2 is a sectional elevation taken on the line 2—2 of Fig. 1.

Fig. 3 is a plan view of the device.

Fig. 4 is an enlarged vertical sectional view similar to Fig. 2 and showing in full and dotted lines the circular motion of the mortar.

Fig. 5 is an enlarged fragmentary vertical sectional view of the device taken on the plane of the section line 5—5 of Fig. 4, and

Fig. 6 is a detailed enlarged fragmentary horizontal sectional view taken on the plane of the section line 6—6 of Figs. 1 and 4 and showing the horizontal motion of the mortar.

Referring to the drawing illustrating the preferred form of the invention for demonstrating the principles thereof, the amalgamator includes a base 10 having one or more cushions or cushioned feet preferably of rubber or the like and

four in number located at each corner of the base, at the bottom thereof, and having a circumferential flange or surrounding rim 12 at the top in connection with one or more holes 13 for receiving the screws or other fastenings to secure the device to a bench, table or other horizontal support. A motor 14, including the usual housing, is mounted on the base 10, and is preferably an electric motor of A. C. or D. C. type, or a combination thereof and has the usual rotor 15 and horizontal shaft 16 thereof. Mounted on one side of the motor housing is a switch 17, and also a time controlled switch device 18 held by a strap 19 and provided with a switch 20 for setting it in motion. The dial face 21 of the control device 18 is marked off or calibrated in seconds from zero to sixty or one minute, and the pointer 22 is turned to any desired point or calibration on the dial according to the number of seconds time duration which it is desired to have the device operate by the running of the motor to cause actuation of the mortar and pestle of the amalgamator or mixing device. Current is supplied to the motor through an extension cord or cable 23, having a plug 24 at the end thereof to connect with a source of power supply, such as the electric current from a wall socket of the wiring of a building, and this wiring also is connected by a cable 25 directly from the socket and from a terminal of the motor field winding or coil to the control device 18 through its switch 20. It will be noted that the front of the base 10 projects forwardly from the motor 14 or housing thereof, and one end of the horizontal drive shaft 16 of the rotor 15 extends at a distance thereover and is threaded externally as indicated at 26. Mounted upon the threaded end of the shaft is an eccentric bushing or sleeve 27 having an eccentric portion or groove 28, which may be arranged at any desired acute angle of 6 degrees or otherwise to the axis of rotation or outer face of the cylindrical portion of the bushing located concentric to the axis, as indicated at 27 and represented in the form of a nut or wrench head of hexagonal or other polygonal shape and having one end or face, namely, its outer face 29 normal to the axis of the shaft 16, and the other or inner face or annular portion 30 forming a shoulder at an intersecting angle to the angle or plane of the face 29 or obliquely or diagonally to said axis. The bushing is in the form of a sleeve and the eccentric portion 28 extends to the outer end thereof with the outer cylindrical surface of the eccentric portion 28 of the bushing 27 disposed at an acute angle to the axis of the motor shaft 16. The outer cylindrical surface of the eccentric bushing or sleeve 27 at the portion 28 may be arranged at an angle of 6 degrees or otherwise to the motor shaft 16, although this angle may be varied as desired and found most expedient, depending upon the materials to be amalgamated, the speed of the motor and other factors. Thus, the outer surface of the bushing or sleeve at the eccentric portion 28 is at right angles with, or normal to the inner-face or shoulder 30 of the flange or portion 27 and at an angle of 6 degrees or otherwise, with the outer face 29 of said flange or bushing 27 and with the sleeve off-center or eccentric with respect to the flange or bushing proper. It will of course be understood that the bushing 27 is provided with a threaded bore 31 to mount the same on the threaded end 26 of the shaft 16, and this bore may be at an angle of 6 degrees or otherwise, with respect to the outer cylindrical surface or eccentric portion 28 of the sleeve or

bushing 27, so that motion transmitted from the shaft will have its direction changed as it rotates in that the surface or eccentric portion 28 of the cylindrical sleeve 27 is at an angle of 6 degrees or otherwise with respect to the shaft 16. This motion will be correspondingly transmitted to a roller or antifriction bearing cage 32 mounted on the eccentric portion 28 and in turn loosely mounted upon the antifriction bearing cage 32 is 5 a split collar support 33 comprising two semicircular sections 34 having apertured ears 35 integral or formed on the ends thereof as by producing the sections of the collar from stampings of resilient or spring material and locked together by 10 15 clamping screws 36. A retractile coiled spring 37 is held between the bottom ears 35 on the screw 36 at this point, and the spring extends downwardly through an opening 38 in the base 10 and is anchored by a pin 39 held across the opening 20 at the bottom of the base in a recess 40. This spring 37 keeps the split collar support from turning with the bushing and shaft and tends to normally hold the support vertical, in addition to absorbing shock and taking up throw, thrust 25 and vibration, but allows slight whipping thereof during the rotation of the shaft when driven by the motor at relatively high speeds for a purpose and advantage to be hereinafter more fully explained. 30 The semicircular sections 34 of the split collar 33 are formed as parts of relatively T-shaped stampings, or the like, having intermediate legs or spring arms 41, which facilitates manufacture of the support. These arms are disposed intermediate the ends of the collar sections 34 and arranged vertically on edge to extend horizontally and axially or outwardly away from the end of the shaft 16 to form mortar supporting means. The arms are bent or curved inwardly as at 42 at 35 intermediate points to form a contraction, and adjacent their ends are provided with opposed cups 43 of somewhat semispherical form with their concaved sides disposed toward each other in spaced parallel relation, and preferably having 40 central openings 44. These cups are also provided with grasping projections 45 at their extremities to facilitate spreading of the cups to receive a mortar or capsule 46, which is designed to hold the ingredients or materials to be amalgamated or mixed. The mortar consists of a hollow cylindrical chambered body 47 provided with a hollow cap 48, and both of these parts preferably have semispherical rounded ends 49 to fit the concavities of the spring arms to releasably hold the mortar in position. It is to be noted that the spring arms extend horizontally but vertically on edge and in a plane of a horizontal diametrical line through the shaft and split collar beyond the end of the shaft over the portion of the base extending forward from the motor to support the capsule in a normally horizontal position under the action of the spring 37, instead of extending upward, and this greatly facilitates the insertion and removal of the mortar, as well as providing for compactness and eliminating a projection above the motor housing. It also provides for a motion of the mortar and pestle together with the ingredients in the mortar which gives a more efficient mixing motion. The roller bearing cage 32 on the eccentric portion 28 of the bushing or sleeve 27 is held on the sleeve by a collar 50, the threaded bore of which engages the threaded end 26 of the shaft against the outer end or face 51 of the bushing which is disposed at an intersecting angle to the angle or plane of the face 29, ob-

liquely or diagonally to the axis of the shaft 16. The inner face 52 of the collar 50 registers with and engages the outer end of the cage 32 and is disposed at the same angle as the end 51 of the sleeve or bushing 21, which it engages. The outer face 53 of the collar 50 is disposed at right angles or normal to the threaded bore thereof and the shaft, including the threaded portion which it engages, but the inner face 52 of the collar is arranged at an angle of 6 degrees or otherwise to the outer face 53 which is perpendicular to the shaft and at an intersecting angle to the angle or plane thereof and the bore or vice versa, the inner face of the collar thus being eccentric to the shaft. A hexagonal or other cap nut 54 threads on the shaft to hold the bushing in position.

It will thus be seen that since the split collar and support are retained against turning or rotation by the spring 37 or other means provided for the purpose, the bushing will revolve within the antifriction or roller bearing cage, and as the high point of the eccentric bushing 21 revolves, it will cause the split collar support 33 to be moved in such a manner that the mortar 46 will be moved in a circular back and forth and up and down motion in a substantially diamond shaped, oval or circular path in a vertical plane, and also receive a horizontal side to side motion with the mortar changing the direction of axes at each revolution. That is, the mortar is oscillated vertically and laterally on a horizontal axis and simultaneously reciprocated in an arcuate path or oscillated to take a swinging motion back and forth with each vertical lateral oscillation. The mortar will be oscillated on its central transverse axis, which passes axially through the shaft and simultaneously reciprocated or oscillated on its longitudinal axis and be moved up and down in an arc on a horizontal axis as it is moved in a circular path in a vertical plane in a somewhat gyrating, eccentric or universal movement, instead of being oscillated on a vertical axis and simultaneously reciprocated or oscillated back and forth on a horizontal axis as in the prior construction. The particular advantage of this motion is that the substance to be amalgamated is shaken in practically every essential way and more efficiently than the human hand would shake it. It is not merely oscillated about an axis, but is so moved that the mortar changes the direction of the axes during every revolution. A better mixing effect is produced by having the mortar take an arcuate reciprocating motion longitudinally or oscillating on its longitudinal axis and horizontally moving on a vertical axis, instead of on a horizontal axis, as previously, and simultaneously oscillating the mortar on its central transverse axis substantially at right angles to the axis of the first motion, which transverse axis passes axially through the drive shaft so that the motion is a substantially diamond shaped or oval shaped circular motion in a vertical plane on a horizontal axis. This path is represented by the dotted oval or diamond shaped outline A in Fig. 4, in which the solid line position of the mortar is at the top and substantially horizontal, while the dotted line position B at the bottom corresponds thereto, and between these positions the mortar is inclined at opposite sides as indicated by the oppositely inclined or sloping sides of the relatively concentric circular, oval or diamond shaped path A. On the other hand, Fig. 6 shows the opposite positions of the mortar in its horizontal arcuate motion, in which it is oscillated or reciprocated to swing back and forth in a horizontal

plane on a vertical axis. The other motion, as previously stated, is on a horizontal axis passing axially through the shaft. While arranging the axis of the cylindrical surface of the bushing at an angle of 6 degrees to the shaft is preferable, this angle may be varied. Fig. 1 represents the position of the bushing as indicated, also in full lines in Fig. 5 and the dotted line position in the latter figure indicates the position of the mortar and the mortar holding arms after the bushing has been moved to 180 degrees further in its revolution. In the intermediate positions at either side, when the bushing has been turned 90 degrees from either of the positions shown in solid and dotted lines in Fig. 5, the mortar and mortar supporting arms will be oppositely inclined at either side above or below the axis of the shaft, which gives the vertical oscillation of the mortar and pestle 55 therein together with the materials being mixed. This motion is on the central transverse axis of the mortar and due to the action of the restraining means or spring, a snapping or whipping action is provided at the end of each motion to cause a corresponding motion of the material and end thrust of the pestle or pellet therein, together with a sliding motion of the rounded ends of the pellet against the correspondingly arcuate concave ends of the mortar chamber with a somewhat sliding motion to effectively grind and triturate the mixture more thoroughly and in less time than previously required. In Fig. 5 the letter C indicates a point on the axis on the cylinder of the cylindrical surface of the bushing and the bushing turns horizontally on this axis during every revolution. In this way, as the bushing rotates, the mortar travels in a circular manner but in a relatively diamond shaped or oval path vertically and changes or reverses the direction of the axes of the mortar as it moves from an upper to a lower position and back again as it moves from a lower to an upper position in its rotary path. In addition, the mortar is oscillated on its central transverse axis and on a horizontal axis axially of the shaft in addition to the motion from side to side and changes the direction of its axes in each revolution of the bushing. In this way, particularly in conjunction with the operation of the pestle within the mortar, the amalgamation is assisted and speeded up.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In an amalgamator, a motor, a shaft operated by said motor, a cylindrical bushing eccentrically mounted on said shaft, mortar supporting means loosely mounted on said bushing and comprising a split clamp with spring arms intermediately at right-angles thereto and extending in the direction of the shaft, said arms being spaced apart and having mortar receiving portions, and means to prevent rotation of the mortar supporting means with the shaft.

2. In an amalgamator, a motor driven shaft, a cylindrical bushing eccentrically mounted on said shaft with its longitudinal axis at an acute angle

to the shaft, mortar supporting means loosely mounted on said bushing normal to the bushing and comprising a split clamp having semi-circular clamping portions connected at their ends and intermediate spring arms normal thereto and extending in the same direction, said arms springing inwardly and adapted to hold a capsule mortar therebetween, and means to hold the mortar supporting means against turning with the shaft.

3. In an amalgamator, the combination with a driven shaft, a collar mounted eccentrically on the shaft and held against turning therewith, said collar having spaced spring arms with sockets and normally moving toward each other to grip the ends of a capsule mortar and adapted to spring apart to release the mortar, said arms being horizontally aligned beyond one end of the shaft.

4. In an amalgamator, a driven shaft, an anti-friction bearing mounted eccentrically on the shaft and restrained against rotation therewith, a split collar fixed to the bearing and comprising semi-circular portions with intermediate spring arms normally thereto and extending axially in spaced relation to grip and hold a mortar therebetween, and means to release said arms from the mortar.

5. In an amalgamator, a motor driven shaft extending horizontally, a bushing on said shaft fixed to rotate therewith, the longitudinal axis of said

bushing intersecting the axis of the shaft at an acute angle, a collar on said bushing, resilient means attached to said collar to prevent the collar member from rotating with the shaft, and arms 5 extending substantially axially from said collar and spaced apart beyond the end of the shaft to resiliently grip and hold a capsule mortar at the ends thereof, rotation of said shaft causing the mortar to oscillate on a horizontal axis at oppositely inclined positions and horizontal intermediate positions above and below the axis of the shaft in a vertical path and on its central transverse axis which passes axially through said shaft and simultaneously oscillating the same on its 10 longitudinal axis and horizontally on a vertical axis substantially at right-angles to the axis of the first motion.

6. In an amalgamator, a split collar comprising semi-circular resilient portions having ears at the ends thereof, connecting means for holding co-acting ears in clamping relation to a member encircled thereby, said semi-circular portions having intermediate spring arms normal thereto in substantially T-shaped formation and facing each 15 other in alignment horizontally, said arms having opposed concavities for receiving the ends of a capsule mortar and extensions for releasing said mortar by spreading the arms apart, said arms normally sprung toward each other.

EDWARD L. CHOTT.
